UNITED STATES PATENT OFFICE.

ROBERT W. BETTS, OF NEW YORK, N. Y.

IMPROVED BOX FOR MUSTARD AND THE LIKE ARTICLES.

Specification forming part of Letters Patent No. 42,549, dated May 3, 1864.

To all whom it may concern:

Be it known that I, ROBERT W. BETTS, of the city and State of New York, have invented, made, and applied to use a certain new and useful Improvement in Boxes for Mustard and other Articles; and I do hereby declare the following to be a full, clear, and exact description of the said invention, reference being had to the annexed drawings, making part of this specification, wherein—

Figure 1 is an elevation of said box, and Fig. 2 is a vertical section of the same.

Similar marks of reference denote the same parts.

Boxes for containing mustard and other substances have heretofore usually been made of metal, which is unnecessarily costly, as said boxes are usually destroyed when empty. Wood has been employed in connection with metal rims at the end, and boxes made entirely of paper are well known.

The nature of my said invention consists in a box formed with a paper body and end inclosed by a metal base and flange, and provided with a cover having a metal rim. A box formed in this manner is much cheaper than those heretofore made, at the same time having a neat appearance; and in consequence of the manner of putting on the flanged base or bottom the paper forming the sides is so confined to the interior paper base that the parts cannot accidentally become separated. This mode of constructing boxes produces a new and useful article of manufacture.

In the drawings, *a* is a cylinder, of paper of suitable thickness, or of card or paste board,

the edges of which are to be lapped and glued together, so as to form a sufficiently strong cylinder.

b is the circular or other shaped piece of card-board or paper, forming the inner end at the bottom of the box; and *c* is the metal base to said box with a flange turned up on its edges, as at 1 1. This flange 1 1 is to be slightly conical, in order that the metallic base *c* cannot be disconnected from the lower end of the cylinder *a*. This flange may be pressed into this conical form after the base has been put on the box; but if the flange of said metal base is first formed tapering or conical, the bottom end of the cylinder *a* may be forced out into it by pressing in the paper or pasteboard end *b* after said cylinder has been set into the metallic flanged base.

d is the cover of the box, made of metal, with the rim 2 passing over the outside of the cylinder *a*, and capable of easy removal.

A label or wrapper of thin paper may be pasted around the box, as shown by the red lines.

What I claim, and desire to secure by Letters Patent, is—

The box of paper or pasteboard with an inner end, *b*, of similar material, and inclosed by the metallic flanged base or end *c*, as set forth.

In witness whereof I have hereunto set my signature this 19th day of March, 1864.

ROBERT W. BETTS.
